UNITED STATES PATENT OFFICE.

WILLIAM K. FARRAND, OF BROOKLYN, NEW YORK, ASSIGNOR OF ONE-
THIRD TO MARIE A. HILL, OF BROOKLYN, NEW YORK.

HANGER FOR AWNINGS, &c.

SPECIFICATION forming part of Letters Patent No. 716,016, dated December 16, 1902.

Application filed May 2, 1901. Serial No. 58,488. (No model.)

To all whom it may concern:

Be it known that I, WILLIAM K. FARRAND, a citizen of the United States, residing at Brooklyn, in the county of Kings and State 5 of New York, have invented certain new and useful Improvements in Hangers for Awnings, &c., of which the following is a specification.

This invention relates to hangers for awnings, window-shades, and similar devices; and it has for its object to provide an improved hanger of this class which will be capable of ready attachment and detachment and will be superior in positiveness of operation and 15 general efficiency.

In the drawings, Figure 1 is a perspective view of a window-frame provided with my improved hanger and illustrating an awning supported by the same. Fig. 2 is a detail end 20 view of one member of my improved hanger, showing the parts in operative position. Fig. 3 is a detail sectional view of the same. Fig. 4 is a detail end view of another member of the improved hanger. Fig. 5 is a detail sectional 25 view of the same. Fig. 6 is a detail vertical sectional view of another member of my improved hanger. Fig. 7 is a detail transverse sectional view of the same, taken upon the line 7 7, Fig. 6.

Corresponding parts in all the figures are 30 denoted by the same reference characters.

Referring to the drawings, 1 designates my improved hanger as applied to a window and supporting an awning.

The improved hanger consists of three members 2, 3, and 4, respectively, Figs. 2, 4, and 6, of which the members 2 and 3 are applied to the horizontal awning-support 5 and the member 4 is applied to the tilting or folding awning-frame 6.

The member 2, Fig. 2, consists of two elements 7 and 8, respectively, of which the element 8 is designed to be permanently secured to the window-frame 9 and the element 45 7 is adjustably carried by the horizontal awning support or rod 5. The member 7 is formed to interlock with the member 8 and consists of a collar 10, which is threaded upon one end of the rod 5 and is provided with a projecting head 11, which is adapted to be received by the element 8. The head 11 is provided with a transverse perforation or opening 12, Fig. 3, through which a nail or other suitable

implement may be passed to cause the rotation or adjustment of the collar 10 upon the 55 rod 5. The element 8 of the member 2 consists of a bracket-piece 13, which is arranged in a plane at right angles to the line of extension of the rod 5 and is provided with a transverse irregular slot 14, which forms a shoulder 15, beneath which the head 11 may be fitted by rotation or adjustment of the collar 10. The slot 14 opens at the top of the bracket-piece 13, whereby the head 11 may readily be inserted into the same and fitted beneath the 65 shoulder 15. The head 11 is engaged with and disengaged from the shoulder 15 by rotating or adjusting the collar 10 by means of a nail or other implement which may be applied to the same in the opening 12. 70

The member 3 is identical in construction with the member 2, with the exception that in substitution for the irregular shoulder-forming slot 14 the bracket-piece 13 is provided with a rectangular slot 16, in which the 75 head 11 exactly fits. In applying the transverse member or rod 5 to the bracket-piece 13 the head 11 of the member 3 is first passed through the slot 16 in the bracket-piece 13 of the member 3, and the head 11 of the member 2 is then passed downwardly into the slot 14 in the bracket-piece 13 and is turned into position for locking engagement with the shoulder 15. The transverse support or rod 5 is then securely locked in position against 85 inadvertent detachment.

The member 4 consists of two elements 17 and 18, respectively, of which the element 17 is slidably mounted upon the customary vertical guide-rods 19 and the member 18 is carried by the awning-frame 6. It will be understood that the said awning-frame is of bowed formation, as customary, and carries at each end one of the adjustable elements 18, there being also two of the guide-rods 19 95 and two sliding elements 17, carried, respectively, by said guide-rods. Each of the elements 17 consists of a collar 20, which is loosely mounted upon one of the guide-rods 19 and is provided with a projecting portion 21, 100 consisting of parallel spaced angular keepers 22. Each of the adjustable elements 18 consists of a collar 23, which is threaded upon one end of the awning-frame 6 and is provided with a projecting T-head 24, which is fitted between the keepers 22 when

- 23 has been suitably adjusted and which will be prevented from withdrawal from the keepers 22 when the collar 23 is suitably further adjusted. The collar 23 is provided with a transverse slot or opening 25, through which a nail or other suitable implement may be passed for the purposes of adjustment of the element 18 in connecting the T-head 24 with the keepers 22 and in disconnecting the former from the latter.
- The operation and advantages of my improved hanger will be readily understood. The horizontal support 5 may be readily connected with the window-frame by inserting the head 11 of the member 3 in the slot 16 in the bracket-piece 13 of the member 3 and then inserting the head 11 of the member 2 in the irregular slot 14 in the bracket-piece 13 and adjusting the collar 10 to engage said head 11 beneath the shoulder 15 and prevent the withdrawal of the same from the slot 14. To disconnect the horizontal support 5 from the bracket-pieces 13, the collar 10 of the member 2 is adjusted or rotated sufficiently to disengage the head 11 from the shoulder 15, and said head 11 is then withdrawn from the slot 14, which permits the withdrawal of the head 11 of the member 3 from the slot 16 in the bracket-piece 13 of the member 3. To connect the awning-frame 6 with the guide-rods 19 in operative vertically-adjustable and pivotally-movable position, the T-heads 24 are passed between the keepers 22 of the collar 20, and the collars 23, which carry the T-heads, are then rotated or adjusted to bring the T-heads into planes transversely of the keepers, in which position they are prevented from detachment from the sliding elements 17. It will be understood that when the awning-frame is raised into folded or vertical position the T-heads rest upon the projecting portions 21, which are secured to the collars 20, and thus firmly support the awning-frame. The angular formation and spaced relation of the keepers 22 permit of free movement of the T-heads 24 in connection with the keepers 22 in the pivotal movement of the awning-frame. The collars 20 of the sliding elements 17 move freely upon the guide-rods 19 in adjusting the awning-frame. The awning-frame may be hoisted and lowered in the customary manner by means of cords connected with the same and passing over pulleys 26, which are sustained by the horizontal awning-support 5.
- My improved hanger may be applied to a wide variety of shapes and styles of awnings, as well as to window-shades, curtain-poles, and other devices.
- I do not desire to be understood as limiting myself to the details of construction and arrangement as herein described and illustrated, as it is manifest that variations and modifications may be made in the features of construction and arrangement in the adaptation of the device to the various conditions

of use without departing from the spirit and scope of my invention and improvements. I therefore reserve the right to all such variation and modification as properly fall within the scope of my invention and the terms of the following claims.

Having thus described my invention, I claim and desire to secure by Letters Patent—

1. In a device of the class described, means for connecting the awning-frame with the window-frame, comprising two separate elements one of which consists of a cap adjustably mounted upon the awning-frame and provided with a projection, which is rectangular in cross-section and extends diametrically across the outer surface of the closed end of said cap, and the other of which is carried by the window-frame and formed to receive said projection and to lock the same against withdrawal by the adjustment of said cap.

2. In an improved hanger of the class described, means for connecting the awning-frame with the window-frame, comprising two elements one of which is adjustably connected with the awning-frame and embodies a T-head and the other of which embodies two spaced keepers arranged to receive said adjustable element in locking engagement.

3. In an improved hanger of the class described, means for connecting the awning-frame with the window-frame comprising two elements one of which is connected with the awning-frame and the other of which is connected with the window-frame, said first-named element consisting of an adjustable collar provided with a projecting T-head, and said last-named element consisting of a slideable collar provided with spaced angular keepers which are formed to receive said T-head in locking engagement.

4. The herein-described means for connecting awning-frames with the vertical guide-rods which are secured to the window-frame, comprising an adjustable element connected with one end of the awning-frame and a slideable element connected with each of said vertical guide-rods, each of said adjustable elements consisting of a collar which is threaded to one end of the awning-frame and is provided with a projecting T-head, and each of said slideable elements consisting of a collar which is mounted upon one of said guide-rods and is provided with two angular spaced keepers which are connected each at its ends with said slideable collar, said slideable element being formed to receive said adjustable element in locking engagement.

In testimony whereof I have signed my name in the presence of the subscribing witnesses.

WILLIAM K. FARRAND.
